UNITED STATES PATENT OFFICE.

AUGUSTUS KELLOGG SLOAN, OF BROOKLYN, NEW YORK.

BINDING-POST.

1,200,537.

Specification of Letters Patent. Patented Oct. 10, 1916.

Application filed July 25, 1913. Serial No. 781,128.

To all whom it may concern:

Be it known that I, AUGUSTUS KELLOGG SLOAN, a citizen of the United States, and a resident of Brooklyn, in the county of 5 Kings and State of New York, have invented certain new and useful Improvements in Binding-Posts, of which the following is a specification.

The invention relates to what are known 10 as "binding posts" which are used for making electrical connections.

It relates more particularly to a device of this character having special features of universal adaptability in conjunction with 15 well known types of terminal connectors.

The object of the invention is to provide a binding post of the character described adapted to receive any of the well known forms or types of terminal connectors and 20 with features of relatively non-rotary parts which prevent loosening of the parts of the binding post in use and the occurrence of a microphonic contact.

A further object is to produce a simple 25 and effective arrangement of parts wherein the clamping members will be held against relative rotation by a simple arrangement of the elements making up the structure.

Referring to the drawings: Figure 1 is a 30 view in elevation of the device embodying the invention. Fig. 2 is a vertical sectional view on enlarged scale. Fig. 3 is a perspective view of the various parts in unassembled position arranged in the relative position 35 of assembly. Fig. 4 is a plan view of the base and conducting post. Fig. 5 illustrates a modified form of the structure. Fig. 6 is a sectional view of the device embodying a modified arrangement of eccentric parts, the clamping parts being closed. Fig. 40 7 is a similar sectional view with the parts open. Fig. 8 is a detail perspective view of the various parts in position for assembly. Fig. 9 is a top plan view of the base with the 45 spindle in section. Fig. 10 illustrates a modified method of arranging an eccentric spur in the clamping part.

Binding posts are very common in the art and have been made in a great variety of 50 forms. The simplest type is that employing a nut and washer mounted upon a threaded spindle, said nut and washer serving as a clamping device for binding a terminal connection which has been wound about the threaded spindle. Many forms 55 of clamping devices have been employed in

conjunction with binding posts for securing a terminal connection. In all such devices, so far as known, the clamping members usually comprise a base-piece with a co-operating clamping washer and nut or similar clamping device threaded upon a spindle which project from or through the base. When the terminal connector is attached, it is located between the base and the clamping washer. In such devices, the clamping washer has been of a type free to rotate upon the spindle. At any rate, it has not been positively held against rotation and after the wire or terminal connector is 60 in place and tightly clamped, movement of the conductor will loosen the clamping nut upon its threaded spindle and thus impair the electrical connection.

It is one of the principal objects of the 75 present invention to provide a simple device in which the direct clamping parts are of a relatively non-rotary character so that, a terminal connection, when once bound between them is securely and positively held 80 and, even jarring or working of the conductor, will not loosen the clamping members.

One of the objects of the present invention is to provide a device, with these advantages, which will be of very simple form 85 and may be readily and cheaply manufactured, insuring proper fitting of the parts.

In Figs. 1 to 4 of the drawings, there is 90 shown a simple eccentric arrangement of the parts which provides for the non-rotary feature of the clamping member yet provides all the elements of a universal binding post. In Figs. 6 to 10 there is illustrated 95 an eccentric arrangement of parts which also prevents relative rotation of the binding elements.

In a patent issued to me March 19th, 1912, No. 1,020,457, there is illustrated a 100 binding post in which the clamping elements are of a non-rotary character. In the device shown in said patent, the members must be concentrically arranged with reference to each other and formed with considerable accuracy to insure proper fit and, of course, where a squared or angular enlargement is employed upon the conducting post of the device, the movable clamping member which fits over said part must be broached out to fit accurately over the enlargement.

In the device herein described, it is possible 110 to use in place of the angular en-

largement, a circular enlargement or equivalent means which will have no sharp corners against which the terminal connector must be cramped and which will provide against rotation of the clamping member.

5 Referring to the drawings, the numeral 1 denotes a base-piece and 2 a coöperating clamping member. The base-piece 1 is of semi-spheroidal form as at 3 and has a cylindrical neck 4 joining it with a cylindrical foot-piece 5 of substantially the same diameter as the largest periphery of the semi-spheroidal part 3. Extending through the base is a threaded opening 6 into which 10 is screwed the shank 7 of a conductor having an enlarged portion 8 and an upper screw-threaded portion 9 which is engaged by a clamping nut 10.

15 The clamping member 2 is of substantially semi-spheroidal form and when set down against the semi-spheroidal section 3 of the base, the two parts provide a spheroidal surface which will receive one type of terminal connection.

20 25 The nut 10 is provided at its upper end with a tubular extension 11 which also is of a proper size and form to receive another terminal connection. Connections of different types may also be attached to the reduced portion of the base 4. It will thus be seen that the exterior of the binding post is adapted for receiving connectors of various types and two or more connectors may be used at the same time upon the device.

30 35 To prevent relative rotation between the base and the coöperating clamping member 2, the enlarged portion 8 of the conducting post is arranged slightly eccentric to the threaded portions 7 and 9, the latter being 40 in concentric relation to the base 1, clamping member 2 and nut 10. The eccentrically arranged enlargement 8 extends above the upper surface of the base-part 3 and presents a smooth round surface about which a 45 terminal connector may be wound without liability of its becoming engaged with the threaded portion of the conducting post. The clamping member 2 has an eccentric

50 55 perforation 12 adapted to fit over the enlargement 8. This clamping member 2 is in engagement with the nut 10, although said nut is free to turn relatively thereto. Thus, whenever the nut 10 is turned upon the threaded conducting post 9, the clamping member 2 will be raised or lowered with reference to the base 1 although held against relative rotation with reference thereto and with reference to the conducting post by the slightly eccentric arrangement of the enlargement 8. As a convenient means of effecting a connection between the nut 10 and the clamping member, a slight groove is formed in the lower peripheral edge of the nut as at 14. The upper edge 15 of the 60 65 clamping member 2 is spun into said groove.

This gives an extremely smooth finish to the exterior of the binding post and is all sufficient as a connection between the nut and clamping member.

The conducting post, as illustrated, may 70 extend through the base 1 for any required distance and through a washer 16 and clamping nut 17, the fixed terminal connection may be secured directly to the conducting post.

75 In order to provide a direct connection to the conducting post, perforations 18 may be formed through the enlargement on a line with the upper surface of the base and when a conductor is inserted in said perforation, it 80 may be securely held therein by the clamping member 2.

85 From the above it will be seen that the binding post as a whole, is truly universal in its application. The spheroidal outer surface of the clamping member and base provide for one type of terminal connection, the tubular extension 11 for still another, the reduced portion of the base 4 for another, to say nothing of the various forms 90 which may be applied between the clamping member 2 and base part 3. It will also be observed that the base portion, coöperating clamping member and nut at the points of their greatest diameters are substantially 95 uniform and may be made from the same piece of stock. The perforation 12 which fits over the enlargement 8 may be very easily formed without broaching and similarly the conducting post may be readily 100 formed from round stock. The device constructed as herein described obviates the necessity of fine broaching tools and workmanship such as required in the use of stock of angular cross-section and yet provides 105 against the relative rotation of the clamping parts.

110 In lieu of securing the non-rotative features by means of an enlargement 8 eccentrically arranged with reference to the center of the conducting post, the clamping member may have an eccentric pin as illustrated in Fig. 5.

115 When the construction of Fig. 5 is used, the enlargement 20 upon a conducting post 118 21 may be concentric with reference thereto and the recess 22 of the clamping member 23 may also be concentric with reference to the opening 24 through which the threaded stem 25 passes.

120 125 A pin 26 may be secured in a drilled hole 27 projecting into the clamping member 23 and extending slightly within the periphery of the recess 22. This pin when engaged with a groove 28 milled from the side of the enlargement 20 will serve to prevent relative rotation of the parts.

Obviously, various arrangements of eccentric members might be employed without departing from the spirit or intent of 130

the invention and in any of said devices, a substantially smooth circular enlargement will be provided about which the terminal conductor may be wrapped and then clamped by the clamping member, with no possibility of a relative rotation of the clamping parts. Furthermore, the device has all the advantages of universal application of connectors and embodies the feature of a direct continuous conducting post formed from a single piece of metal without joints of any character.

What I claim as my invention and desire to secure by Letters Patent is:

15 1. A binding post comprising a base and clamping member, for clamping a wire, said clamping member being concentrically arranged with reference to the base and provided with an eccentric opening, an eccentric conducting member of cylindrical form mounted on the base and having an extended spindle projecting concentrically through the base and through the clamping member, said interengaging eccentric conducting part 20 and opening of the clamping member adapted to prevent relative rotation of said clamping members and base as the clamping member is raised and lowered with reference thereto, and means engaging the spindle and 25 the clamping member for raising and lowering said clamping member.

2. A binding post comprising a base, an integral electrical conductor extending therethrough and provided with an enlargement 35 of cylindrical form eccentrically arranged with reference to the base and the axis of the integral conductor and providing a wiring connection, a clamping member having a recess eccentrically arranged and sliding 40 over said eccentric enlargement, and a clamping nut in engagement with said clamping member for moving it axially of the binding post whereby said clamping member will be raised and lowered by manipulation of the nut to clamp a wire encir- 45

cling the eccentric enlargement of the conductor.

3. A binding post comprising a base, a threaded spindle concentrically arranged with reference thereto, an eccentric member of cylindrical form appurtenant to said spindle between the base and a clamping washer, said clamping washer having an eccentric recess fitting said eccentric member and a nut engaging the threaded spindle and clamping washer axially movable upon the spindle and adapted to raise and lower said clamping member. 50 55

4. A binding post comprising a base and support, a conductor concentrically arranged with reference thereto and having an eccentric enlargement of cylindrical form projecting above the base, a clamping washer concentrically arranged with reference to the base and conductor and provided with an eccentric recess fitting about said eccentric enlargement, and a clamping nut threaded upon the conductor and concentrically arranged with reference to the base and clamping washer, engaging the latter for raising and lowering said washer while it is held against rotation by the eccentric enlargement, and adapted to clamp said washer with reference to the base. 60 65 70

5. In an electrical connector comprising a base, a clamping member appurtenant thereto, a nut in engagement with said clamping member for raising and lowering it with reference to the base, a threaded spindle intermediate the base and nut, and means eccentrically arranged between the base, nut and clamping member for preventing relative rotation of the clamping member and base while permitting relative axial movement of the clamping member upon the threaded spindle. 75 80 85
